ADJUSTABLE LOOSE LEAF BINDER

Filed July 15, 1932

Inventor
John J. Gaertig
By Ernest E. Tupes

Att:

UNITED STATES PATENT OFFICE

JOHN J. GAERTIG, OF CHICAGO, ILLINOIS

ADJUSTABLE LOOSE LEAF BINDER

Application filed July 15, 1932. Serial No. 622,592.

The invention relates to loose leaf binders adapted for permanently filing loose papers and more particularly it relates to adjustable binders providing improved means for 5 clamping the file contents closely together to form permanent volumes adapted to be numbered or stenciled in consecutive order and placed on end on shelves in the same manner as books or other permanently 10 bound publications.

The device is especially adapted for use in binding files or documents which must be preserved for a long period of time and which are intended to be destroyed or disposed of as waste paper following the date 15 upon which they become obsolete.

The binder may be used advantageously regardless of whether the forms to be preserved comprise a large or small number 20 but its use is found to be particularly advantageous when the daily or weekly accumulation of documents is voluminous as is the case in central offices of railroad companies where the annual accumulation fills 25 several thousand binders of a maximum thickness convenient for handling and storing. The uniform documents used by railroad companies and their preservation for a definite number of years in compliance 30 with the regulations and orders of the Interstate Commerce Commission necessitates the accumulation of many thousands of binders of a thickness of three or four inches or greater. The preservation of such records 35 for the required time and the labelling or indexing of the same for convenient access at any time during the period they are required to be preserved entails a heavy expense. It is a common practice in such cases 40 to stencil or otherwise mark the backs of the files in consecutive order and to stand the same on end on shelves side by side in the same manner that books are positioned on library shelves. The vault space required 45 to store the voluminous files for the required period makes it desirable that the file contents be removed and destroyed or disposed of as waste paper as soon as the required period of preservation has expired. In order 50 that the filled binders might be arranged

compactly side by side on shelves it has been the practice heretofore to use unitary rigid backs, preferably of sheet metal covered with fabric, to which backs cardboard or paper covers are attached. Backs heretofore constructed as described are expensive and in removing the file contents at the expiration of the required period of preservation substantially all of such backs are so mutilated and distorted as to be incapable 60 of further use and as a result an entirely new supply must be provided for each year's files. The outlay for new backs and binders in the case of many railroad companies amounts to several thousand dollars annually.

An object of the invention is the provision of an improved binder which is easily disassembled for the removal of obsolete 70 contents and is capable of repeated use whereby substantial economies and savings are effected.

Another object of the invention is the provision of an improved binder of the kind described having an adjustable back and 75 novel means for clamping the contents of the binder together to provide permanent volumes of various degrees of thickness between predetermined limits.

A further object of the invention is the provision of an improved binder of the kind described which is simply constructed, inexpensive to manufacture, easily assembled and disassembled and satisfactory for its 80 intended purpose.

Many other objects and advantages of the construction herein shown and described will be obvious to those skilled in the art from the disclosure herein given.

To this end my invention consists in the 90 novel construction, arrangement and combination of parts herein shown and described, and more particularly pointed out in the claims.

In the drawing, wherein like reference 95 characters indicate like or corresponding parts,

Fig. 1 is an edge view, partially in section, of a binder embodying the principles 100 of the invention;

Fig. 2 is a plan view partially in section of a portion of the binder shown in Fig. 1;

Fig. 3 is a perspective view of an angle iron and headed sleeves mounted thereon;

5 and

Fig. 4 is a perspective view of another angle iron and headed sleeves adapted for assembly in adjustable cooperating relation with the angle iron and sleeves shown in 10 Fig. 3, the angle irons in both Fig. 3 and Fig. 4 being shown without fabric sheet covers.

Referring now more particularly to the drawing, the assembled binder, designated 15 generally by the numeral 10, is shown in Fig. 1 partially in section. The binder comprises covers 11 and 12 respectively fastened to L shaped back members 13 and 14 by fabric sheets 15. The fabric sheets 15 20 are fastened to the L shaped back members 13 and 14 and to the covers 11 and 12 by adhesive material not shown. The back members 13 and 14 are preferably constructed of rigid material such as sheet metal and the 25 covers 11 and 12 may be constructed of cardboard or similar material. The member 13 preferably has a length approximately equal to the width of the covers 11 and 12. The member 14 has inturned ends 30 providing flanges 16. The flanges 16 are spaced away from the cooperating leg of the member 14 to provide channels 17 in which one leg of the member 13 is slidably mounted. The flanges 16 are closely spaced to the non-cooperating leg of the member 14 to add 35 rigidity thereto. The cooperating legs of the members 13 and 14 are preferably of substantially the same depth and thereby permit maximum adjustment of the thickness 40 of the binder between predetermined limits. The minimum thickness of the binder is equal to or slightly greater than the depths of the cooperating legs of the members 13 and 14 and the maximum thickness is slightly less than the combined 45 depths of the members 13 and 14.

The outstanding legs of the members 13 and 14 are connected by adjustable fastening means adapted to clamp said legs in 50 contact with the contents of the binder when filled between minimum and maximum limits determined by the depth of the cooperating legs of the members. The fastening means comprise one or more sleeve members 18 projecting inwardly through the outstanding leg of the member 13 and a corresponding number of sleeves 20 mounted on and projecting inwardly from the outstanding leg of the member 14 in aligned 55 inner telescoping relation with the sleeves 18. The sleeve 18 is preferably slightly longer than the depth of the cooperating leg of the member 13 and the sleeve 20 is slightly shorter than the depth of the cooperating leg of the member 14. The sleeves 60

20 are provided with heads 21 covered by the fabric 15 which holds the sleeves permanently in position. The sleeves 18 are provided with heads 19 overlying the outer fabric 15 and are wedged in position in apertures provided for that purpose in the member 13. The sleeves 20 are internally threaded and are engaged by screw bolts 22 mounted in the sleeves 18. The bolts 22 are provided with screw heads 23 which enable the bolts to be engaged with and disengaged from the sleeves 20 by the use of a screw driver. The assembled binder is shown in Fig. 1 with the fastening device arranged intermediate the positions of minimum and maximum capacity. The minimum capacity of the binder with the contents clamped between the outstanding legs of the back corresponds to the position wherein the lower edge of the cooperating leg of the member 13 is positioned in the bottom of the channels 17. The maximum capacity is obtained when the lower edge of said leg is positioned in the top of the channels 17.

The binder contents are perforated before filing so as to be mounted on either the sleeves 18 or 20 and the binder is disassembled by separating the members 13 and 14. In filling the binder to capacity the documents to be filed are placed in the desired order on the section comprising the outer cover 12 and back member 14 and also on the section comprising the cover 11 and the back member 13 both sections in general being separately filled to capacity.

The filled sections are then assembled by inverting the section comprising the cover 11 and the member 13 and positioning the sleeves 18 over the corresponding sleeves 20. The bolts 22 are then inserted in the sleeves 18 and threaded into the sleeves 20 until the file contents are firmly clamped together. The bolts 22 are preferably of the same length as or slightly longer than the sleeves 18 and require only a few turns of the bolt to clamp the back sections in contact with the contents when the binder is filled to maximum capacity. The bolts 22 are threaded for their full length and enable the contents to be clamped together when the binder is filled to any extent between maximum and minimum. The described construction provides a maximum capacity substantially ninety-five percent greater than the minimum capacity of the binder.

Thus it will be seen that I have provided a binder of the kind described which is simple in construction, easily assembled and disassembled, adjustable between predetermined minimum and maximum limits and wherein the maximum capacity is approximately double that of the minimum capacity. The construction provides a loose leaf binder adapted for permanent storage of documents, from which the contents may be easily

and quickly removed and leaves the binder adapted for repeated use for an indefinite period of time.

Having thus described my invention, it is obvious that various immaterial modifications may be made in the same without departing from the spirit of my invention; hence, I do not wish to be understood as limiting myself to the exact form, construction, arrangement and combination of parts herein shown and described or uses mentioned.

What I claim as new and desire to cover by Letters Patent is:

1. In a binder of the kind described, a pair of covers and a back comprising two L-shaped members, one leg of each of said members being arranged in cooperating relation with the corresponding leg of the other, inturned flanges on the ends of one of said cooperating legs providing channels in which the corresponding ends of the other of said cooperating legs are slidably mounted, inturned flanges on one of the non-cooperating legs and closely spaced therefrom to provide rigidity to said non-cooperating leg, means connecting the covers with the projecting non-cooperating legs of said members, adjustable fastening means connecting said non-cooperating legs, said fastening means comprising an inwardly projecting sleeve mounted on one of said non-cooperating legs, an inwardly projecting sleeve mounted on the other of said non-cooperating legs in aligned telescoping relation with said first mentioned sleeve and a screw bolt extending through one of said aligned sleeves into threaded engagement with the other sleeve, each sleeve having substantially the same length as the depth of the cooperating leg of the member on which it is mounted, the length of said screw bolt being slightly greater than the depth of the cooperating leg of one of said members and slightly shorter than the cooperating leg of the other of said members.

2. In a binder of the kind described, a pair of covers and a back comprising two rigid L-shaped members of a length approximately equal to the width of said covers, one leg of each of said members being arranged in cooperating relation with the corresponding leg of the other, inturned flanges on the ends of one of said cooperating legs providing channels in which the corresponding ends of the other of said cooperating legs are slidably mounted, inturned flanges on one of the non-cooperating legs and closely spaced therefrom to provide rigidity to said non-cooperating leg, fabric strips hingedly connecting the covers with the projecting non-cooperating legs of said members and providing a covering for said L-shaped members, adjustable fastening means connecting said non-cooperating legs, said fastening means comprising a plurality of inwardly

projecting sleeves mounted on one of said non-cooperating legs, a plurality of inwardly projecting sleeves so mounted on the other of said non-cooperating legs as to telescope within said first mentioned sleeves, the outer ends of said last mentioned sleeves being covered by one of said fabric strips, and a plurality of screw bolts each extending through one of said aligned sleeves into threaded engagement with the other, each set of sleeves having substantially the same length as the depth of the cooperating leg of the member on which they are mounted, the length of said screw bolts being slightly greater than the depth of the cooperating leg of one of said members and slightly shorter than the cooperating leg of the other of said members.

In witness whereof, I hereunto subscribe my name this 12th day of July A. D., 1932.

JOHN J. GAERTIG.
